CLAIM

The ornamental design for a textile with a camouflage pattern, as shown and described.

DESCRIPTION

FIG. 1 is a top plan view of a textile with a camouflage pattern according to the present invention;

FIG. 2 is a reference view thereof with broken lines shown therein to indicate the area comprising the detail view; and, FIG. 3 is an enlarged detailed view of the area 3 circumscribed within FIG. 2.

The broken lines surrounding FIGS. 1 and 2 depict the boundaries of the claim and form no part thereof. The broken lines within the boundaries of FIG. 2 and surrounding FIG. 3 indicate the area of the detail view and form no part of the claimed design.
